G. W. BROOKS

LOCKER DOOR

Filed Sept. 11, 1925

UNITED STATES PATENT OFFICE.

GEORGE W. BROOKS, OF TOPEKA, KANSAS.

LOCKER DOOR.

Application filed September 11, 1925. Serial No. 55,733.

My invention relates to locker doors and more particularly to a door for hallway lockers, small rooms, wall openings or other enclosures or spaces to which private access is desirable, but where because of lack of hall space or for other reasons it is either impractical or undesirable to employ a door of the ordinary hinged type; the object of the invention being to provide a door of this character which is simple in construction and operation, attractive in appearance, and through which privacy of access to the space which it encloses may be afforded.

In the accompanying drawings wherein the invention is, for the purpose of illustration, shown as applied to a hallway locker,

Fig. 1 is a perspective view of a locker equipped with a door embodying my improvements, parts of the locker and of the door being broken away for better illustration, the door being shown in open position.

Fig. 2 is a similar view of the door closed, and

Fig. 3 is a detail perspective view of a modified form of the invention, showing the locker door in connection with a door of ordinary construction and provided with a ventilating attachment.

Referring more in detail to the drawings, 30 1 designates a locker which may be of any suitable type, inset into a building wall or otherwise arranged, and comprising a frame 2 and shelving 3, although the construction of the locker frame is immaterial 35 providing a suitable door opening is afforded.

Pivotedly mounted on the inner edges of the side members of the frame 2 by studs or the like 5 are hanger bars 6, preferably of 40 strap metal and provided at their lower ends with links 7 which are pivotally connected with the free ends of the bars by studs 8, and are provided with longitudinal slots 9. The bars 6 are paired at the top and bottom of the frame, the upper pair being connected with the frame adjacent the top rail, and the lower pair at such a distance from the bottom rail that the bars may move into and from the door opening 4. The hanger 45 bars are adapted for carrying a door member 10 which forms a closure for the door opening and may be moved from and toward the frame 2 upon its suspension mounting in a manner presently described. The door is 50 preferably formed of sheet metal and comprises the face 11 and edge flanges 12, the

dimensions being such that the edge flanges will bear against the outer face of the door frame adjacent the opening 4 when the door is closed, and the length of the hanger bars 60 being such that when the door is open a sufficient space is afforded between the edges of the door and the face of the frame 2 to permit articles being inserted into the locker or removed therefrom. 65

The door member is preferably connected with the hanger bars by means of brackets 13 secured to the inner faces of the side flanges 12 by bolts or rivets 14 and having screw threaded studs 15 adapted for slidable 70 projection into the slots 9 of the links 7 on the hanger bars, so that the door may be easily assembled with its mounting and properly adjusted thereto.

To facilitate opening of the door I prefer 75 to provide mechanism for automatically swinging the door to open position when it is unlocked, and to accomplish this purpose I locate a combination locking and operating mechanism within the locker and preferably 80 comprising a rod 17 mounted for vertical sliding movement in brackets 18 that are fixed to and project inwardly from one of the side members of the door frame and through a lock housing 19 which is also 85 mounted on the door frame. The rod 17 is also fixed in apertures in lugs 20 rotatable on the free ends of the bars 21 which are pivotally connected with the hanger bars 6, 90 preferably through the same studs 8 which connect the bars with the links 7, and located between the upper stud 20 and the adjacent bracket 18 is an expansion spring 95 22 which normally urges the rod downwardly and tends to swing the bars 21 outwardly to automatically open the door under the spring tension. The rod 17 is provided with a notch 23 adapted for engagement by a lock bolt 24 within the lock housing 19 when elevated against the tension of the spring 22, 100 but which may be released to free the rod by the withdrawal of the bolt through a lock mechanism which may be of any ordinary construction and is therefore not illustrated in detail. 105

Assuming that the parts are constructed and assembled as described, when the door is in closed position the hanger bars 6 lie within the door frame in the position illustrated in Fig. 2, and the combined locking and operating rod is held in its vertical position against tension of its spring by engage-

ment of the lock bolt in the notch 23. When the holder of the key desires access to the locker he inserts the key, rocks the lock bolt to free the rod 17 and immediately upon removal of the bolt from the rod, the spring operates to throw the rod downward, this movement extending the bars 21 and pushing the door outwardly on its pivotal hanger mounting, the projection of the door being sufficient to afford access to the locker through the space between the edges of the door flanges and the door frame.

When the door is to be closed the user merely presses the door toward the frame, this pressure swinging the hanger links back against the tension of the spring 27 so that the rod 19 is elevated and the notch 23 again brought into position for receiving the locking bolt. When the door has been closed it is automatically locked as heretofore described.

It is apparent that with this construction a greater number of lockers may be employed in a limited hall space than would be possible with doors of ordinary hinged construction.

In the modified form shown in Fig. 3 I have illustrated my improvements as applied to an ordinary hinged door wherein the locker space is provided by a built up housing on the side of the hinged door opposite that to which my structure is applied. With this arrangement I may provide for ventilation by cutting an opening 25 in the housing 26 and equipping the latter with a panel 27 which may move toward and from the housing on extension arms 28 to open and close the ventilating aperture 25.

What I claim and desire to secure by

Letters-Patent is:

1. In combination with a door frame and a door, links fixed to the door and extending into the door opening, hanger bars pivotally mounted on the frame within the door opening and pivotally connected with said links, guides on the frame, a rod slidable in said guides, spreader bars pivotally connected with said links and with said rod, a spring normally, yieldingly urging the rod in one direction and lock mechanism normally restraining the rod to retain the door in closed position.

2. In combination with a door frame and a door, links adjustably mounted on the door and extending into the door opening, hanger bars pivotally mounted on the frame within the door opening and pivotally con-

nected with said links, guides on the frame, a rod slidable in said guides, spreader bars pivotally connected with said links and said rod, an expansion spring surrounding the rod, and yieldingly urging the rod in one direction, and lock mechanism normally restraining the rod to retain the door in closed position.

3. The combination of a door frame and a door, of a hanger comprising hanger links having their opposite ends respectively connected to the door and door frame, spreader bars each having one end connected to the door and its other end pivotally mounted on the door frame on a shiftable axis, and means urging the frame ends of said bars to shift their axes and open the door.

4. The combination with a door frame and a door, of a hanger bar having its opposite ends respectively connected with the door and door frame, a spreader bar having one end connected to said door and its opposite end pivotally mounted on the frame on a shiftable axis and in spaced relation to an adjacent end of the hanger bar, the spacing of said ends being variable whereby the door is moved from and toward the frame upon variation of the spacing of said ends of said hanger and spreader bar.

5. The combination with a door frame and door, of hanger bars pivotally connected with the frame and door, a vertically reciprocating rod mounted on the frame, a stop on the frame, a stop on the rod, a spring on the rod between said stops normally tending to shift the rod, means for restraining the rod, spreader bars pivotally connected with the rod, and means pivotally connecting said spreader bars with the door whereby the spacing of the frame ends of said hanger and spreader bars may be decreased when the rod is shifted in one direction.

6. The combination with a door frame and door, of hanger bars pivotally connected with the frame and door, a vertically reciprocating rod mounted on the frame, a spreader bar pivotally connected with the rod, and means pivotally connecting said spreader bar with the door whereby the spacing of the frame ends of said hanger and spreader bar may be increased to open the door when the rod is moved in one direction.

In testimony whereof I affix my signature.

GEORGE W. BROOKS.
